EARTH ANCHOR

William J. Binkley, Warrenton, Mo., assignor to
 Binkley Mfg. Company, Warrenton, Mo., a corporation of Missouri

Application February 2, 1948, Serial No. 5,852

5 Claims. (Cl. 189—92)

1

This invention pertains to earth anchors of the type which are placed in a prepared hole and subsequently expand therein by means of a tamper rod.

It is a general object of the invention to provide an anchor of the type described which may be manufactured at minimum cost, is more easily transported, may be shipped and stored in a minimum amount of space and one which may be easily and quickly assembled for use.

Other objects and advantages will become apparent as the specification proceeds and a more comprehensive understanding of the invention will be afforded from the following detailed description when considered in conjunction with the accompanying drawing, in which,

Figs. 1, 2 and 3 are front, side and top views, respectively, of an earth anchor embodying the instant invention in a preferred form thereof and showing the same as it is assembled for placement in an earth hole before the anchor is expanded, and

Fig. 4 is a side view of the anchor after the same has been expanded.

Fig. 5 and Fig. 6 are exploded side and horizontal views, respectively, of the instant invention as shown in Figs. 2 and 3.

In its preferred embodiment, the anchor comprises two identically formed anchor plates 11 and 12 which are supported upon a spreader plate 13. Each of the anchor plates 11 and 12 have interlocking hinge portions 14 and 15, later to be described in detail, through which are passed an anchor rod 16. The latter element, which is provided with a threaded end 17, is also passed through the spreader plate 13 where its threaded end engages with and is threaded into a nut 18 held in place within a nut retainer 19 secured to the underside of the spreader plate 13.

The hinge portion 14 of the anchor plate 11 comprises a rectangular section 21 in which is cut an elongated slot 22, a tongue 23 (Fig. 2) and an L-shaped section 24. Similarly, the hinge portion 15 of the plate 12 is formed with a rectangular section 25 in which an elongated slot 26 is cut, a tongue 27 and an L-shaped section 28. The rectangular sections 21 and 25 and the L-shaped sections 24 and 28 form respectively the female and male parts of two separable hinges which lie on opposite sides of the rod 16 (Fig. 3) when the identical plates 11 and 12 are placed in opposed interlocking relationship with each other for support on the spreader plate 13. When thus assembled the sections 24 and 28 are passed into

2

the slots 26 and 22, respectively, and moved laterally until they occupy the positions which they assume in Fig. 3. As illustrated in Fig. 2, the sections 21 and 25 and the sections 24 and 28 are bent so that the parts of the sections 24 and 28 which lie above the sections 25 and 21 are depressed, and so that the parts of the rectangularly shaped sections 21 and 25 which lie above the sections 28 and 24 are likewise depressed.

10 This, in effect, gives to the assembled anchor a top which is substantially flat as viewed in Fig. 2.

The tongues 23 and 27 are substantially straight and underlie, respectively, portions of the sections 21 and 25 as shown in Figs. 2 and 3. They serve the purpose of providing stops, each of which lies on opposite sides of the anchor rod 16, to hold the hinges of the composite anchor in locked position as shown in Fig. 3. In other words, when the sections 24 and 28 are initially passed into the slots 26 and 22 the tongues 23 and 27 are displaced inwardly toward the center to occupy positions where neither underlie any portion of the rectangular sections 21 and 25. Thereafter the anchor plates 11 and 12 are moved laterally relatively to each other until the parts occupy their positions shown in Fig. 3, in which case the inwardly disposed ends of the sections 21 and 25 together with a rounded cutout 29 in the plate 11 and a similar cutout 31 in the plate 12, bound an opening 32 in the composite hinge section of the assembled anchor through which the anchor rod 16 is passed. When the rod is thus passed into the assembled anchor, the tongues 23 and 27 which lie on opposite sides thereof prevent reverse lateral displacement of the two anchor plates 11 and 12 thus locking the male hinge sections 24 and 28 in place.

With the anchor rod 16 passed into the opening 32 as aforesaid, the latter element is carried through a hole in the spreader plate 13 and secured thereto by means of the nut 18, previously described. When thus assembled, the anchor plates 11 and 12 are supported on top of the spreader plate 13 so that a toe section 33 of the former and a toe section 34 of the latter rests on a rounded top surface 35 of the spreader plate 13. For the purpose of holding the anchor assembled during the time which it is placed in the ground, separate frangible tie wires are passed through a hole 36 and a hole 37 formed in the toe sections of the anchor plates 11 and 12 into aligned holes bored in the spreader plate 13.

In use, the anchor is assembled as best shown in Fig. 2 and is placed in a hole in the earth

which has been prepared therefor. Thereafter, by means of a tamping rod, the anchor plates 11 and 12 are forced downwardly along the anchor rod 16 until they occupy the position shown in Fig. 4. This action moves the toe sections of the anchor plates outwardly into the undisturbed earth to anchor the end of the rod 16 permanently therein or until such time as it is salvaged by unscrewing it from the spreader plate and withdrawing it from the ground. In the course of spreading the anchor plates the rounded portion 35 of the spreader plate 13 serves as a cam to engage the toe sections 33 and 34 of the anchor plates and turn them outwardly as the tamping blows are applied all in a well known manner. Further, it is to be pointed out that the corrugations which are made in each of the anchor plates 11 and 12 form locking areas 38 and 39 (Figs. 2 and 4) which pass over the rounded upper surface 35 of the spreader plate 13 as shown in Fig. 4 and thereafter lock the anchor plates in their outward or expanded position.

With further reference to the hinge sections 14 and 15 which are bent as above described, it is to be noted that when the composite anchor is spread, the male and female hinge sections only are bent. Thus, they bend along a line 41 which passes substantially through the center of the composite hinge section of the anchor so that the complementary hinge sections of the individual anchor plates extend substantially vertically and abut each other as shown in Fig. 4, there being no bending action at the points 42 and 43. This carries the tongues 23 and 27 into the positions indicated in Fig. 4 and limits the bending of the hinge sections to areas thereof which prohibit the possibility of any fracture to the anchor plates at critical points. It is to be noted that the controlled bending action of the hinge sections 14 and 15 is achieved at the desired points, that is, parallel and centrally between the edges 42 and 43 along line 41, by reason of the slots 22 and 26 weakening that portion of the hinge as compared to the rigid, stronger construction present at the points 42 and 43. Likewise, the L-shaped sections 24 and 28, being weaker than the edges 42 and 43, react to pressure similarly. In addition, the preformed bends in the hinge sections 14 and 15 assist in localizing the bending action to the area.

While no limitation as to the material to be used is intended, the anchor herein described possesses the advantage that it may be manufactured as a die formed steel anchor. It may, therefore, be made much more cheaply than other anchors of its general type, and the savings which its use may obtain are pronounced when compared with cast or malleable iron anchors. Moreover, since each of the anchor plates 11 and 12 are identical, a plurality of them may be nested one within the other for the purposes of transportation or storage, and when so arranged, they will occupy a minimum amount of space. Still further, the construction of the anchor plates is such that two of them can be interlocked and assembled with an anchor rod and a spreader plate very quickly and easily. This feature of the invention provides for an anchor which may be transported to its point of use disassembled. Also, the component parts of the anchor need not be sacked or connected with bolts or wires during transportation to assure that all parts of the anchor reach their point of use.

Various changes may be made in the details of construction, within the scope of the appended

claims, without departing from the spirit of this invention. Parts of the invention may be used without the whole and improvements may be added while retaining some or all of the advantages of the invention.

What is claimed is:

1. In an earth anchor having a pair of anchor plates between which an anchor rod is passed for attachment to a spreader plate upon which latter element said anchor plates are supported and over which they are spreadable, the improvement comprising means for interconnecting said anchor plates consisting of a female and male hinge section formed as a part of each of said anchor plates respectively said male sections being passed into said female sections, and a stop formed on each of said anchor plates each of which is adapted to lie adjacent to and on opposite sides of said rod to lock said male hinge sections.

2. In an earth anchor having an anchor rod and a spreader plate attached thereto which is adapted to support a pair of anchor plates and over which said anchor plates are spread, the improvement comprising two-separate but identically formed hinge sections, a male and a female hinge section formed on each of said anchor plates, said anchor plates being supported on said spreader plate in opposed relationship each with the other and with the male hinge section of one anchor plate passed into the female hinge section of the other to form a hinge on opposite sides of said rod, and a stop formed on each of said anchor plates each of which is adapted to lie adjacent to and on opposite sides of said rod to lock said male hinge sections in said female hinge sections.

3. In an earth anchor having a pair of anchor plates between which an anchor rod is passed for attachment to a spreader plate upon which latter element said anchor plates are supported and over which they are spreadable, the improvement residing in a hinge for connecting said plates comprising a female hinge section formed on one of said anchor plates, a male hinge section formed on the other of said anchor plates and passed into said female section to hinge said plates together, and preformed bends made in both of said hinge sections whereby said hinge sections will bend along lines within each when said anchor plates are forced downwardly over said spreader plate.

4. In an earth anchor having a pair of spade shaped anchor plates with toe portions thereof supported on a concaved spreader plate to which is attached an anchor rod passed between said plates, the combination with a hinge for connecting said anchor plates comprising a rectangularly shaped hinge section formed on a first of said anchor plates at substantially a right angle to the body thereof and having an elongated slot cut therein, an L-shaped hinge section formed on a second of said anchor plates at substantially a right angle to the body thereof, said L-shaped section being passed into the slot of said rectangularly shaped section and displaced longitudinally of said slot, and a tongue formed on said second anchor plate at a spaced distance from said L-shaped hinge section adapted to lie adjacent to said rod and lock said L-shaped hinge section in said rectangularly shaped hinge section.

5. An anchor plate formed as a unitary metal stamping comprising a spade-like member having toe and body sections, a rectangularly shaped

hinge section formed on one side of said body section at substantially a right angle thereto and having an elongated slot therein, an L-shaped hinge section formed on the other side of said body section at substantially a right angle thereto, a tongue formed on said body section intermediate said hinge sections, and preformed bends made in both of said hinge sections to cause the outer half portions of each to lie in a plane above the inner portions thereof.
